UNITED STATES PATENT OFFICE.

JASPER M. WALTERS, OF FINDLAY, OHIO, ASSIGNOR OF TWO-THIRDS TO
WILLIAM W. SHULER AND H. WALTER DOTY, BOTH OF SAME PLACE.

AIR AND GAS BURNER.

SPECIFICATION forming part of Letters Patent No. 416,130, dated November 26, 1889.

Application filed July 17, 1889. Serial No. 317,783. (No model.)

To all whom it may concern:

Be it known that I, JASPER M. WALTERS, a citizen of the United States, residing at Findlay, in the county of Hancock and State of Ohio, have invented a new and useful Air and Gas Burner, of which the following is a specification.

This invention has relation to air and gas burners, and is adapted for use in steam-boilers, furnaces, or for domestic purposes.

Among the objects in view are to adapt the invention for use in connection with any ordinary heating apparatus, whether domestic or otherwise, and to provide therein means whereby the air that is subsequently mixed with the gas is primarily heated, afterward mixed in a suitable receiver or mixing-chamber, and then discharged into the combustion-chamber; to so construct the apparatus as to provide a continuous circulation of hot air, and also to obviate the objectionable and usual whistling and roaring noise caused by the draft of air passing from the mixing-chamber.

With these general objects in view the invention consists in an imperforate spherical or other shaped mixing-chamber, from which there lead the air and gas pipes, terminating in a burner, a gas-pipe leading to and communicating with the mixing-chamber, and a hot-air pipe communicating with the furnace above its fire-box and with the mixing-chamber, whereby a circulation of hot air takes place.

The invention also consists in certain other features hereinafter specified, and particularly pointed out in the claims.

Referring to the drawings, Figure 1 is a transverse vertical section of an ordinary boiler provided with an air and gas burner constructed in accordance with my invention. Fig. 2 is a detail in perspective of the invention detached. Fig. 3 shows my invention applied to an ordinary cooking-stove, and Fig. 4 to a heating-stove.

Like numerals of reference indicate like parts in all the figures of the drawings.

Referring particularly to Fig. 1, 1 represents an ordinary steam-boiler of the horizontal type, and below the same is arranged the usual fire-box 2, and above this boiler and communicating with the fire-box the smoke-

stack 3. From any suitable source of supply there leads the gas-pipe 4, provided near the boiler with a suitable valve 5, and terminating, preferably below the floor, in an imperforate spherical chamber or mixer 6. Extending from the chamber 6 and up through the bottom of the fire-box is the combined gas and air pipe 7, the rear end of which communicates with the chamber 6, and at its upper end there is formed the usual transversely-disposed perforated burner-pipe 8, which lies directly under the boiler and in a position to deliver the burning flame of gas and air directly to the surface thereof.

9 represents the hot-air pipe, the open or induction end of which is preferably flared or bell-shaped, as at 10, and the opposite or ejection end communicates with the chamber 6.

In Fig. 1, wherein I illustrate my invention as applied to a steam-boiler, I have, for the purpose of securing the best results, located the flared induction end of the pipe 9 directly above the fire-box 2 and within the smoke-stack, whereby the heated air arising from the fire-box is induced by the draft to enter the pipe 9, and is conducted from thence into the chamber 6.

In practicing my invention the pipes 9 and 7 are constructed considerably larger than the gas-pipe 4. The valve 5 being closed, it will be noticed that the receiver and the pipes 9 and 7 are filled with air. The valve being opened, the pressure of gas forces the air from the pipe 7, and the air from the pipe 9 is induced to descend into the receiver 6. The flame, being ignited, heats the air, and the same is carried to the pipe 9 and again to the receiver, thus keeping up a continuous circulation of hot air. The effect of such a mixing of hot air with the gas previous to its reaching the point of combustion is well known and will be readily appreciated, as I effect a saving in the consumption of the gas.

Referring to Figs. 3 and 4, it is apparent that the only modification necessary in practicing my invention in this class of stoves is to locate the induction end 10 of the pipe 9 at a suitable point, or where the greatest draft of hot air occurs.

If desired, I may provide the hot-air pipe 9 with a valve, (shown by dotted lines in Fig.

1,) whereby the circulation of air does not take place until the air above the burner has become heated, when said valve is opened. Such a construction also prevents an upward 5 rising of the gas through the pipe 9 when the valve 5 is first opened. This tendency, however, is overcome by the pipe 4 terminating near to the eduction end of the pipe 7.

By reason of forming the mixing-chamber 10 imperforate the whistling, roaring noise so objectionable is avoided and the gas deodorized.

Having thus described my invention and its 15 operation, what I claim is—

1. In a burner of the class described, the combination, with a mixing-chamber, of a burner-pipe leading therefrom and terminating in a burner, a gas-supply pipe terminating in said chamber, and a hot-air pipe communicating 20 with said chamber and terminating in a line of draft with the burner, substantially as specified.

2. In a burner of the class described, a mixing-chamber, a supply-pipe, and a gas and air 25 pipe extending therefrom and terminating in a burner, in combination with a hot-air pipe communicating with the chamber and having its opposite end flared and arranged above the burner, substantially as specified.

3. In a burner of the class described, a mixing-chamber, an air and gas pipe leading 30 therefrom and terminating in a burner, a hot-air pipe terminating in the mixing-chamber and projecting upwardly and terminating 35 at its opposite end in a flared receiver arranged above the burner, and a gas-supply pipe provided with a valve and terminating

in the mixing-chamber and in line with the air and gas pipe, substantially as specified.

4. The combination, with a steam-boiler 1, 40 having the fire-box 2 and the smoke-stack 3, of the mixing-chamber 6, located near the boiler and having the enlarged gas and air pipe 7, terminating in the burner 8, and the enlarged hot-air pipe 9, communicating with 45 the chamber and terminating at its opposite end in the flared mouth 10, located in the smoke-stack, and the gas-pipe 4, smaller than the pipes 7 and 9 and provided with the valve 5, and terminating in the mixing-chamber 50 and opposite the pipe 7, substantially as specified.

5. In an air and gas burner, the imperforate chamber 6, having a burner-pipe 7, terminating in a burner, the hot-air pipe 9, terminating in the flared mouth 10, and the gas-supply pipe 4, terminating in the mixer, all 55 combined as specified.

6. The combination, with a steam-boiler 1, of the mixing-chamber 6, located near the 60 boiler and having the gas and air pipe 7, terminating in the burner 8, and the hot-air pipe 9, communicating with the chamber and terminating at its opposite end in the flared mouth 10, located in the smoke-stack, and the 65 gas-supply pipe 4, leading to the mixing-chamber, substantially as specified.

In testimony that I claim the foregoing as my own I have hereto affixed my signature in presence of two witnesses.

JASPER M. WALTERS.
